UNITED STATES PATENT OFFICE.

EBENEZER HILL, JR., OF NORWALK, CONNECTICUT.

PLUG-COCK.

No. 823,779.

Specification of Letters Patent.

Patented June 19, 1906.

Application filed June 29, 1905. Serial No. 267,632.

To all whom it may concern:

Be it known that I, EBENEZER HILL, Jr., a citizen of the United States, residing at Norwalk, in the county of Fairfield and State of Connecticut, have invented a new and useful Plug-Cock, of which the following is a specification.

This invention relates to a plug-cock which is unlocked so that it may be opened by the insertion of a key and is locked so that it cannot be surreptitiously opened by the withdrawal of the key. This cock is particularly adapted to be used for controlling the flow of fuel from the reservoir to the engine of an automobile or motor-boat which it is desirable to prevent tampering with. It is also very serviceable as an outlet-cock for tank-wagons and for tanks, barrels, and other receptacles containing liquids which at times are left more or less exposed to preclude the accidental leakage of or clandestine withdrawal of liquid.

The object of the invention is to provide a simple and tight cock which when closed cannot be opened without the insertion of the proper key, but which when open can be easily and quickly closed and securely locked by simply turning and withdrawing the key.

The invention resides in a cock having an easily-turned but tightly-packed plug and a secure cylinder-lock so arranged and combined in a solid body that the plug is released by the insertion of the proper key and is opened by turning the key, which cannot be removed until turned to locking position, which turning of the key always closes the plug.

Figure 1 of the accompanying drawings shows a side elevation of the cock and a key for manipulating the lock and turning the plug. Fig. 2 shows a plan of the cock. Fig. 3 shows a side elevation with the body cut in vertical longitudinal section. Fig. 4 shows a side elevation with a part of the body, the packings, and the packing-nuts cut in transverse section. Fig. 5 shows a plan and an elevation of the plug, and Fig. 6 shows a plan and section of one of the packing-nuts.

The body 1 of the cock may be cast to the desired shape of any metal, preferably brass or bronze. The tapering plug 2 is ground so as to tightly fit the tapering wall of the plug-chamber in the body and has a port 3, which is adapted to register with the fluid-passage through the body.

The hub 4 of the body is extended up-

wardly, and in the hub, about the stem 5 of the plug, is a packing 6, which is forced against the large end of the plug by a nut 7, that has an exterior thread which fits an interior thread in the hub. This nut when turned down forces this packing closely against the large end of the plug and holds the plug down in the tapering chamber and also prevents the leakage of any fluid up around the stem of the plug. Above this nut is a packing 8, the exterior of which fits the threads in the wall of the hub, and above this packing is a nut 9, which when screwed down in the hub expands this packing so that fluid cannot leak between the threads and the packing.

In the upper part of the hub is a cylinder 10, containing the usual spring tumbler-pins 11, which hold the cylinder against rotation until the proper key is inserted in the slot 12. The cylinder is secured in place by turning the upper edge of the hub over a washer 13, that is set in the end. Two lugs 14 extend downwardly from the lower part of the lock-cylinder either side of the reduced upper end of the plug-stem.

When the proper key is inserted in the slot in the cylinder, the locking-pins are withdrawn after the manner common to cylinder-locks, allowing the cylinder to be turned by the key. When the cylinder is turned, the lugs which project below engage the stem of the plug and turn the plug, so as to open or close the passage through the cock.

In the washer that is fastened in the upper end of the hub and that retains the cylinder in place is a curved slot 15, and extending upwardly into this slot from the end of the cylinder is a stud 16. This stud engages the ends of the slot for determining the amount of movement of the cylinder and the plug.

The cylinder-lock shown is one of those in which when the proper key is inserted the cylinder is unlocked and can be freely turned by the key; but the key cannot be removed until the cylinder is turned back to the locking position, when the withdrawal of the key allows the pins to lock the cylinder against movement. The cylinder and the plug are so connected that when the key is in locking position and can be withdrawn the plug is so turned as to close the passage through the cock. By this means the key is always held in position ready to close the cock if the cock is open, and the key cannot be withdrawn unless the cock is closed.

The two packings insure a tight cock, while

allowing the plug to be sufficiently loose to turn freely. One packing prevents any leakage of fluid around the stem of the plug, and the other prevents any leakage past the 5 threads around the inner wall of the hub. The two nuts which keep the packings tight and assist in holding the plug in position also act as lock-nuts to prevent either nut from turning loose when the plug is turned.

10 A cock constructed in this manner can be easily opened and closed by the proper key and yet will always be tight, so that the cock may be used for controlling the flow of such volatile fluids as gasoline, naphtha, and the 15 like. There are no screws, pins, or other means which are easily removable for holding the plug and lock-cylinder in the body, and the bottom of the body is solid, so that a wrench or screw-driver cannot be applied for 20 turning the plug.

The invention claimed is—

1. A plug-cock having a body with a solid integral wall containing a tapering plug-chamber having an imperforate bottom and 25 a cylindrical lock-chamber, a tapering plug rotatable in the plug-chamber, a cylinder-lock fitting the lock-chamber, means connecting the lock-cylinder and the plug, a washer secured in the outer end of the lock-chamber 30 and holding the cylinder in place, and a key for manipulating the lock and turning the cylinder and the plug, substantially as specified.
2. A plug-cock having a body with a solid 35 integral wall containing a tapering plug-chamber having an imperforate bottom and a cylindrical lock-chamber, a tapering plug rotatable in the plug-chamber, a cylinder-lock fitting the lock-chamber, means connecting the lock-cylinder and the plug, a slotted washer secured in the outer end of the lock-chamber, a pin extending from the end 40 of the lock-cylinder into the slot for determining the movement of the cylinder, and a key for manipulating the lock and turning 45

the cylinder and plug, substantially as specified.

3. A plug-cock having a body with a solid integral wall containing a tapering plug-chamber having an imperforate bottom and 50 a cylindrical lock-chamber, a tapering plug rotatable in the plug-chamber, a cylinder-lock secured in the lock-chamber, means connecting the lock-cylinder and the plug, means above the plug for holding the plug down 55 tightly in the plug-chamber, and a key for manipulating the lock and turning the cylinder and plug, substantially as specified.

4. A plug-cock having a body with a tapering plug-chamber and a cylindrical lock-chamber, a tapering plug rotatable in the plug-chamber, a cylinder-lock secured in the lock-chamber, means connecting the lock-cylinder and the plug, a packing bearing on the large end of the plug, a nut turning in the 60 body against the outer face of the packing for holding the packing and plug in place and preventing leakage from the plug-chamber, and a key for manipulating the lock and turning the cylinder and plug, substantially 65 as specified.

5. A plug-cock having a tapering plug-chamber and a cylindrical lock-chamber contained in an integral body with an imperforate bottom, a tapering plug rotatable in the 70 plug-chamber, a cylinder-lock secured in the lock-chamber, and connected with the plug, a yielding washer bearing against the large 75 end of the plug and packing the stem of the plug, a nut screwed into the chamber for holding the stem-packing, a yielding washer above this nut and packing the outer wall of the chamber, a nut screwed into the chamber for holding the wall-packing, and a key for manipulating the lock and turning the 80 cylinder and plug, substantially as specified.
